UNITED STATES PATENT OFFICE

GEORGE T. HILLS, OF CHICAGO, ILLINOIS, ASSIGNOR, BY DIRECT AND MESNE ASSIGNMENTS, TO MUSKEGON MANUFACTURING COMPANY, OF MUSKEGON, MICHIGAN, A CORPORATION OF MICHIGAN

FLOOR-SURFACING MACHINE

Application filed November 7, 1927. Serial No. 231,412.

This invention relates to a floor surfacing machine and more particularly to one adapted for use in finishing the exposed surfaces of wood or composition floors, said surfacing machine further adapted to be controlled by an individual and is electrically operated, causing a rotatable abrasively covered finishing drum to travel over a surface which is to be finished or polished.

10 It is an object of this invention to provide a floor surfacing machine wherein the finishing roller or drum is adapted to be slightly tilted or vertically adjusted to permit polishing of portions of the floor which are uneven at the margins or at other points.

It is also an object of this invention to provide a floor surfacing machine with an adjustable spring-controlled dust collector, adjustable with the downward adjustment of 20 the finishing drum and adapted to be automatically elevated with the upward movement of said drum.

It is a further object of this invention to provide an improved floor surfacing machine 25 provided with an improved inverted U-shaped dustbag, the upper end of which is directed downwardly and is provided with a clamping mechanism which may be operated to open the discharge end of the bag for 30 emptying the contents thereof without necessitating the removal of the dustbag from the machine.

It is furthermore an object of this invention to construct a floor surfacing machine 35 of an improved simplified type having a pivoted handlebar mounted on a steering post and connected by means of toggle mechanisms with the finishing drum supporting spider, whereby the drum during the operation of 40 the machine may be moved toward or away from the floor to vary the pressure of the finishing drum on the surface which is being finished.

It is an important object of this invention 45 to provide an improved simplified form of floor surfacing machine wherein the finishing drum and the dust collecting fan are electrically driven, and having the finishing drum and the dust collecting hood adjustable by means of a handle mechanism for

varying the pressure of the drum upon the surface to be finished by said drum, and having means associated therewith for adjusting the drum in its bearings to take care of uneven places in a floor which is being finished. 55

Other and further important objects of this invention will be apparent from the disclosures in the specification and the accompanying drawings.

On the drawings:

Figure 1 is a top plan view of a floor surfacing machine embodying the principles of this invention and having parts broken away.

Figure 2 is a side elevation of the machine with parts broken away.

Figure 3 is a front elevational view of the machine with parts broken away, and with the finishing roller removed.

Figure 4 is an enlarged plan view of the bag-gripping mechanism or clamp mounted 70 on the steering post of the machine which is shown in section, and illustrating the operation of the clamping jaws in dotted lines.

Figure 5 is a fragmentary detail section taken on line V—V of Figure 1.

As shown on the drawings:

The reference numeral 1 indicates a truck frame or carriage having a pivoted castor bracket 2 mounted underneath the rear end thereof with said castor bracket carrying a 80 rotatable castor wheel 3. A stub shaft 6 is supported by a journal bearing 4 in one side of the truck frame 1 and a collar 7. The shaft 6 supports a front wheel 5 outwardly of the journal 4. The bearing collar 7 is integrally 85 formed on one side of a dust intake pipe or extension 8 which is rigidly secured or formed on one side of a fan casing 9, the other side of which casing is provided with a bearing collar 10 which is rotatably supported on a bearing sleeve 11 on which a second front wheel 12 is rotatably supported. The bearing sleeves 4 and 11 are integrally formed on the truck frame 1. Rotatably journalled in the front wheel supporting sleeve 11 is a fan 95 shaft 13 which projects into the fan casing 9 and has mounted on the inner end thereof a fan wheel 14. Secured on the outer projecting end of the fan shaft 13 is a fan pulley 15 provided with a V-shaped peripheral groove 100.

in which a V-cross-sectioned fan driving belt 16 is engaged. The fan belt 16 is also trained around a V-grooved fan driving pulley 17 secured on the projecting end of a motor shaft 18 forming a part of an electric driving motor 19. The motor 19 is removably secured upon the top of the truck frame 1 by means of retaining bolts 20. Connected to the terminal posts 21 of the motor are a pair of conductors 22, to the ends of which a socket 23 is connected.

Secured to the rear of the fan casing 9 is an extension 24 in which a dust outlet pipe 25 is secured. Attached to the projecting outer end of the dust outlet pipe 25 is the lower end of a U-shaped dustbag 26, the curved or bight portion of which is provided with suitable means to permit the bag to be hung from a hook carried on a pipe handle or steering post 27 the lower end of which post is removably secured by means of bolts 28 in a clamp 29 mounted on the rear extension of the truck frame 1.

The discharge end of the dustbag 26 is directed downwardly and is adapted to be closed by pinching the open end thereof between a pair of rubber clamping pads 30 secured on the inner faces of a pair of clamping arms 31 which are pivotally mounted at 32 on a bracket 33 rigidly secured on the steering post 27. Each of the clamping arms 31 is provided with a curved or bowed extension or handle 34. The ends of the bag clamping handles 34 are connected by means of a pair of toggles or links 35. The toggles 35 are pivotally connected one to the other and to one end of a connecting link 36, the other end of which is pivotally connected to a lever or handle 37 which is pivoted at one end on the pivot 32 as clearly illustrated in Figure 4. When the lever 37 is moved from the dotted line position of Figure 4 into the full line position the clamping arms or jaws 31 are closed against opposite sides of the outlet end of the dustbag 26, thereby clamping said bag between the clamping pads 30. With this novel arrangement of a dust collecting bag it is not necessary to remove the bag from the machine in order to empty the same. When a sufficient amount of dust has been accumulated in the discharge end of the bag a dust receiving receptacle may be placed beneath the outlet end of the bag, after which the lever 37 may be moved into the dotted line position of Figure 4 causing the connecting link 36 to actuate the toggles 35, thereby swinging the clamping arms 31 into open position to permit opening of the discharge end of the dustbag so that the contents thereof may be discharged into the receiving receptacle.

The dust resulting from the polishing or finishing of a floor is adapted to be drawn into a dust collector or hood 38 which is secured to the intake end of the fan extension or receiving pipe 8. The fan casing 9, together

with the extension 8 and the dust receiving hood 38, are pivotally mounted on the truck frame as hereinbefore described, allowing the outer tracking end of the dust collecting hood 38 to be raised out of engagement with the floor by means of a heavy coiled spring 39 or the like, one end of which is attached to the fan extension or intake pipe 8 while the upper end is secured to the floor of the truck frame 1. Mounted on the floor of the truck frame 1 and projecting downwardly therethrough is a stop screw bolt 40 adapted to be engaged by the fan casing 9 for the purpose of limiting the upward swing of the dust collecting hood 38 when pulled upwardly by the control spring 39.

Removably clamped by means of retaining nuts 41 in bearing extensions 42 of the truck frame is a shaft 43 having rigidly secured on each end thereof a bell crank arm 44, having integrally formed thereon a finger or extension 45. The extensions 45 are adapted to seat upon the side flanges of the dust intake hood 38 as shown in Figure 2, to hold said hood depressed against the action of the control spring 39 due to the weight of the heavy finishing drum 46. The peripheral surface of the drum 46 is first covered by a pad 47 over which a covering of sandpaper or other abrasive material 48 is applied. The drum 46 is provided with a groove or slot for receiving the ends of the pad 47 and the sheet of abrasive material 48, to hold said abrasive material secured in position on the drum by means of retaining screws or other suitable means. The drum 46 is mounted on a drum shaft 49 which is journalled in the bell crank arms 44 and has rigidly secured on one projecting end thereof a pulley wheel 50. The pulley wheel 50 is provided with a V-shaped groove for receiving an endless V-cross-sectioned driving belt 51. The driving belt 51 is trained around a small pulley 52 engaged on the outer end of the motor shaft 18 outside of the pulley 17. It will be noted that the finishing drum is rotatably supported in a pivoted bracket supported on the truck frame so that the finishing drum may be raised or lowered to vary the pressure of the abrasive covering of said drum on the surface to be finished.

Rigidly secured on the shaft 43 at substantially the middle portion thereof is a block 53 provided with a handle 54 to facilitate the removal of the finishing drum unit from the truck frame when the retaining bolts 41 are released. Secured on the back of the block 53 is a bolt and nut 55 adapted to removably receive the hooked end of a rocker arm 56 engaged thereon. The lower end of the rocker arm 56 is pivotally supported on the front end of an adjustable connecting rod 57, the rear end of which is connected to a bell crank arm 58 secured on a bell crank shaft 59 supported in the rear extension of

the truck frame 1. Secured on one end of the bell crank shaft 59 is a second bell crank arm 60, to the end of which the lower end of a connecting rod 61 is pivotally engaged. 5 The upper end of the connecting rod 61 is pivotally connected to the right-hand handle 62 of a cross arm 63 which is pivotally supported on the upper end of the steering post 27. The cross arm 63 is also provided with 10 a left-hand handle 64.

The operation of the pivoted cross arm or handle mechanism controls the pressure of the drum upon the floor. The downward movement of the handle 62 decreases the pressure 15 of the drum upon the floor while the downward movement of the left-hand handle 64 causes increased pressure of the drum upon the floor. For the purpose of regulating the maximum pressure of the drum upon the floor a control device is mounted on the steering post 27 and comprises a set screw 65 which is supported in an arm or extension 66 secured on the cross arm 63. Pivotally mounted on the steering post 27 is a drum pressure regulating lever 67 provided with a handle extension 68. When a new sheet of sandpaper or abrasive material is engaged on the drum 46 the set screw 65 is adjusted and the lever 67 is raised by means of the handle 68 to receive the end of the set screw 65 seated thereagainst to limit the downward swing of the left-hand handle 64, thereby limiting the pressure of the drum on the floor in order to obtain the maximum cutting efficiency of the new abrasive. This arrangement of the set screw 65 and the lever 67 affords a means whereby the minimum pressure of the drum upon the floor is adapted to be obtained when the abrasive paper is new. After the abrasive paper has been worn down with the use of the limited pressure the lever 67 is swung downwardly by pulling upwardly on the handle 68, thus removing the stop from in front of the set screw 65 allowing the handle 64 to be 20 moved downwardly a greater distance to produce a maximum pressure of the drum upon the floor. This control of the pressure of the abrasive material on the floor affords an arrangement that enables the operator to do considerably more work with a minimum amount of abrasive material.

As illustrated in Figures 1, 2 and 3, an additional metal weight 69 is provided with said weight having a longitudinal slot or groove in the bottom thereof to permit the weight 69 to be seated upon the handle 54 of the block 53 forming a part of the framework in which the finishing drum is supported. The extra weight 69 is provided with a handle 70 for the convenience of handling the same. The extra weight 69 may be used as desired when it becomes necessary to increase the pressure or weight of the finishing drum on the surface which is being finished.

65 An arrangement is provided whereby the

finishing drum may be slightly adjusted with respect to the floor so that either end of the drum may be slightly raised or lowered to tilt the drum the required amount, so that either end of the drum may be used for finishing a floor or surface when the floor is uneven at its edges or at other points. The adjusting or tilting of the drum is accomplished by means of a pair of adjustable screws 71 which are threaded through a portion of the block 53 and contact the upper edge of the middle portion 72 of a spring bar having the ends thereof twisted to form a pair of integral spring arms 73, the ends of which are bolted to extension lugs 74 integrally formed on the bell crank arms 44 which carry the finishing drum 46. The spring bar 72-73 is pivotally mounted at its middle portion and has the adjusting screws 71 contacting the upper edge thereof on opposite sides of the pivot pin of said spring bar. This arrangement permits the drum mechanism to be slightly sprung or tilted whereby uneven portions of the floor may be finished by the finishing drum. Mounted on the steering post 27 is an electric control switch 74^a having two conductors 75 leading therefrom and connected to a plug 76 which is adapted to be coupled up with the socket 23 connected with the terminals of the driving motor 19. 50 Also connected with the switch 74^a is an extension cord (not shown) of any desired length adapted to be connected with a base plug or power socket to permit a source of electrical energy to be conducted to the driving motor. 100

The operation is as follows:

With the parts assembled as illustrated in Figures 1 and 2 and with the finishing drum 46 having a new covering of abrasive material 48 engaged over the pad 47, the machine is adapted to be set in operation by an operator by turning on the electrical switch 74^a to cause operation of the motor 19, which in turn is adapted to impart a drive to the fan wheel 14 by means of the belt 16 while the belt 51 is used for transmitting a drive to the finishing drum 46. The dust collecting hood 38 is held in engagement with the floor by the weight of the drum carrying frame and the drum since the arms 45 of the bell crank arms 44 are positioned to seat on the side flanges of the dust collecting hood, as clearly illustrated in Figure 2. When the abrasive covering 48 of the drum is new the pressure controlling set screw 65 is adjusted for controlling the maximum pressure of the abrasive material on the floor by swinging the control lever 67 upwardly into alignment with the set screw 65 as illustrated in Figure 3.

The machine is pushed over the floor by an operator and the pressure of the drum upon the floor is governed by the pivoted cross bar 63. By pushing downwardly on the right

hand handle 62 the pressure of the drum is diminished, depending upon the distance the drum is raised from the floor. To increase the pressure of the drum the left-hand handle 64 is pushed downwardly. The pressure of the drum is governed by the operation of the connecting rod 61, the bell crank arms 60 and 58 and the connecting rod 57, which is adapted to actuate the hooked rocker arm 56 which is connected to the pivoted drum supporting frame so that the drum may be either raised or lowered, depending upon the direction in which the handles 62 and 64 are moved by the operator. In case additional pressure is required for the drum an extra weight 69 may be placed upon the drum supporting frame handle 54. The dust collecting hood 38 is controlled by the spring 39 which acts to hold the same in contact with the extensions 45 of the drum supporting frame. The upward swing of the dust collecting hood 38 is adapted to be limited by means of the stop screw 40.

As the machine is advanced over the floor the abrasive drum is adapted to finish and polish the surface while the fan wheel 14 is adapted to create a suction in the hood 38 causing the dust on the floor to be pneumatically drawn into the hood to be discharged through the fan outlet pipe 25 to be deposited in the outlet throat of the dust collecting bag 26, the end of which is closed by means of the clamping arms 31.

After the abrasive material 48 on the drum has been used for some time and is worn the pressure control lever 67 is swung downwardly by swinging the handle 68 upwardly, thereby moving said lever 67 out of engagement with the pressure control screw 65, so that the right-hand handle 64 may be swung downwardly a greater distance to permit greater pressure to be exerted on the floor by the finishing drum.

The finishing drum may be tilted with respect to the floor by adjusting the control bolts 71 which act on the pivoted spring bar 72-73 to spring the same a slight amount sufficient to tilt the finishing drum so that uneven edges or portions of the floor may be properly finished.

After a sufficient quantity of dust has been collected in the throat of the dust collecting bag 26 the clamping control lever 37 is adapted to be moved by the operator from the full line position shown in Figure 4 to the dotted line position, thereby causing the connecting link 36 to break the alignment of the toggle bars 35, thereby causing the clamping jaws or arms 31 to be separated to release the mouth of the dust collecting bag 29. A receiving receptacle may be placed under the discharge mouth of the dust collecting bag to receive the contents of said bag. With this arrangement it will be noted that the

dust collecting bag need not be removed from the machine in order to empty the same.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A floor surfacing device comprising a framework, rollers supporting the same, a driving motor on said framework, a dust collecting fan pivotally supported on said framework, a dust collecting hood connected with said fan, a surfacing drum unit removably engaged on said framework and co-acting with said dust collecting hood, a steering post mounted on said framework, a control switch on said steering post, means for connecting the same with said motor, a control mechanism connected with said finishing drum unit, a control handle pivotally mounted on said steering post and connected with said control mechanism to cause the pressure of the drum unit on the floor to be varied depending upon the operation of said pivoted handle, and means mounted on said steering post and on said pivoted handle for regulating the maximum pressure of said finishing drum unit.

2. A floor surfacing machine comprising a roller carriage, a fan unit pivotally mounted thereon, a finishing drum unit pivotally supported on said carriage and co-acting with said fan unit, driving means on said carriage connected to operate the fan unit and said finishing drum unit, a steering post for said carriage, a dustbag connected to said fan unit with the discharge end of said bag directed downwardly, clamping means on said steering post adapted to engage the mouth of said discharge bag to close the same and adapted to be released for emptying the bag without removal from the machine, a control handle pivoted on said steering post, link mechanisms connected to said handle and with said finishing drum unit to permit the pressure of said finishing drum unit to be varied when the handle is operated, and pressure control means mounted on the steering post adapted to be set to limit the maximum pressure of the finishing drum unit on the floor.

3. A floor surfacing machine comprising a roller carriage, a drum finishing unit adjustably supported thereon, a steering post on said carriage, a handle pivoted on said steering post, a pressure control mechanism mounted on said carriage and steering post connected with said pivoted handle and with said finishing drum unit to vary the pressure of said finishing drum unit on the floor, an adjustable set screw device carried by said pivoted handle adapted to be set for limiting

the maximum pressure of said drum finishing unit on the floor, and a member pivotally supported on said steering post positioned to be contacted by said set screw to limit the movement of said pivoted handle in one direction for limiting the maximum pressure of the drum finishing unit on the floor, and permitting said maximum pressure to be increased by swinging said member out of contact with said set screw.

4. In a floor surfacing machine, the combination with a roller carriage, of a steering post for pushing the same, a finishing drum unit adjustably mounted on said carriage, means for driving the same, a control handle pivotally mounted on said steering post, mechanisms operated by the pivotal movement of said handle to vary the pressure of the finishing drum unit on the floor, and co-acting means mounted on said steering post and on said pivoted handle for limiting the maximum pressure of said finishing drum unit on the floor.

5. In a floor surfacing machine, the combination with a roller carriage, a dust collecting unit pivotally mounted thereon, a spring connecting said roller carriage with said dust collecting unit to normally hold the receiving end of said dust collecting unit off of the floor, a finishing drum unit removably and adjustably engaged on said carriage positioned to contact the receiving end of said dust collecting unit to depress the same against the action of said spring, a pressure controlled mechanism on said carriage adapted to be operated to adjust the drum finishing unit with respect to the floor to vary the pressure of said drum finishing unit, and means carried on said drum finishing unit for tilting the same with respect to the floor.

6. A floor surfacing machine comprising a wheel supported frame, a finishing drum unit supported on said frame, said unit comprising a drum and a carrier, said carrier arranged to move said drum bodily and also tilt the same, means operable at will for bodily moving said drum, a dust collector unit comprising a rigid duct pivotally supported intermediate its ends by said frame and having a hood at one end and a dust bag at the other end, a spring tending normally to raise said hood, there being cooperating members on said carrier and said hood for opposing said spring, a fan within said duct supported by a fan shaft which is coincident with the pivoted supports of said duct, a motor on said frame for actuating said drum and said fan, and a handle for guiding said machine having means thereon for controlling said motor.

7. A floor surfacing machine comprising a frame, bearing sleeves formed thereon, a wheel rotatably mounted on one of said sleeves, a stub shaft journalled in the other of said sleeves, a second wheel carried by

said stub shaft, a fan shaft journalled in said first mentioned sleeve, a duct pivotally supported on said first mentioned sleeve and on the inner end of said stub shaft, said duct being provided with a fan chamber, a fan in said chamber on said fan shaft, a surfacing drum, a carrier for said drum removably attached to said frame arranged to move said drum vertically, means for actuating said carrier to move said drum, a hood adjacent said drum and communicating with said duct, a dust bag on the other end of said duct, means for normally urging said hood upwardly, cooperating means on said hood and said carrier opposing said first-mentioned means, and means on said frame for actuating said drum and said fan.

8. A floor surfacing machine comprising a frame, bearing sleeves formed thereon, a wheel rotatably mounted on one of said sleeves, a stub shaft journalled in the other of said sleeves, a second wheel carried by said stub shaft, a fan shaft journalled in said first mentioned sleeve, a duct pivotally supported intermediate its ends on said first mentioned sleeve and on the inner end of said stub shaft, said duct being provided with a fan chamber, a fan within said chamber on said fan shaft, a surfacing drum, a carrier for said drum arranged to move said drum vertically, means for actuating said carrier to move said drum vertically, a hood communicating with said duct behind said drum, a dust bag on the other end of said duct, spring means for normally urging said hood upwardly, cooperating means on said carrier and said hood for opposing said spring, and means on said frame for actuating said drum and said fan.

In testimony whereof I have hereunto subscribed my name.

GEORGE T. HILLS.
